UNITED STATES PATENT OFFICE.

FREDERICK B. TOWNSEND, OF CHICAGO, ILLINOIS, ASSIGNOR TO WILLIAM H. MINER,
OF CHAZY, NEW YORK.

HAND BRAKE.

1,403,210.

Specification of Letters Patent. Patented Jan. 10, 1922.

Application filed September 5, 1919. Serial No. 321,758.

To all whom it may concern:

Be it known that I, FREDERICK B. TOWNSEND, a citizen of United States, residing at Chicago, in the county of Cook and State 5 of Illinois, have invented a certain new and useful Improvement in Hand Brakes, of which the following is a full, clear, concise, and exact description, reference being had to the accompanying drawings, forming a 10 part of this specification.

This invention relates to improvements in hand brakes.

In the operation of flat or logging cars, considerable difficulty has heretofore been 15 experienced in providing an efficient form of hand brake which can be accommodated within the limited space obtainable when the car is loaded with logs or lumber or the like and which brake shall at the same 20 time conform to the safety requirements of the Interstate Commerce Commission. Hand brakes on such types of cars are, of course, located at the end of the car and the brakeman must be able to operate the same while 25 standing on the usual side step of the car. Where a lever is utilized for winding up the chain, the same must be so arranged as to provide a minimum clearance of approximately four inches between all parts of the 30 car and any of the load, in order to conform to safety requirements.

The object of my invention is to provide a simple and efficient hand brake for railway cars and which is particularly adapted 35 for use on logging cars and which at the same time will conform to standard practice.

In the drawing forming a part of this specification, Figure 1 is a top plan view of one corner of a flat car showing my improvements in connection therewith, parts 40 of the car being broken away in order to accommodate the figure on the sheet. Fig. 2 is a side elevation of the construction shown in Fig. 1. Fig. 3 is a horizontal sectional 45 view upon a somewhat enlarged scale corresponding substantially to the line 3—3 of Fig. 4. Fig. 4 is a vertical sectional view taken substantially on the line 4—4 of Fig. 3. Fig. 5 is an end elevational view of the 50 brake mechanism proper and illustrating more clearly the operation of the release lever, the full lines indicating the normal position of the parts and the dotted lines indicating the position of the lever when the 55 release is effected. And Fig. 6 is an enlarged

detail sectional view and illustrating more particularly the pawl mechanism and corresponding substantially to the line 6—6 of Fig. 4.

In said drawing, the flat car is shown as 60 comprising the usual flat floor 10, end sill 11 and side sill 12, the end grab iron 13, side step 14, side grab iron 15 and top grab iron 16. The improved mechanism, as shown, 65 comprises, broadly, the following elements. A vertical brake or chain winding staff A, a housing B, a ratchet wheel C, an operating handle or lever D, a pawl E, a locking dog F, a release element G, and a release lever H. The staff A is mounted in any 70 suitable manner in a stirrup plate or other structure to provide the necessary bearing and has the usual chain winding drum thereon at its lower end. Said staff A extends upwardly through the end sill 11 of 75 the car and at its upper end is provided with a squared or other non-circular section 17 disposed mainly within the housing B. The ratchet wheel C is provided with a hub 18 having an internal recess to accommodate 80 the squared section 17 so that the ratchet wheel C rotates in unison with the staff A. The hub 18 is extended downwardly so as to form a suitable bearing support 19 on 85 the bottom detachable wall 20 of the housing B.

The operating handle or lever D is movable in a horizontal plane and within an arcuate slot 21 formed in the housing B on the side adjacent the main portion of 90 the car. Said lever D is formed at its inner end with an annular sleeve 22 which seats over the upper end of the hub of the ratchet wheel C and is oscillatably mounted thereon. To prevent dirt or other foreign matter getting within the housing, the lever D is preferably formed with oppositely extending 95 arcuate flanges 23—23 that cover the slot 21. Mounted on the bolt or pivot pin 23 carried by the lever D is a gravity actuated 100 pawl 24 which is adapted to drop down into operative engagement with the radially arranged ratchet teeth 25 on the top face of the ratchet wheel C. It is evident that by 105 oscillating the lever D, the ratchet wheel will be rotated in one direction step by step and the lever free to move backward to obtain a fresh hold.

To hold the ratchet wheel and the staff A 110 against reverse rotation when there is ten-

sion on the brake chain, the locking dog F is employed, the same being pivotally mounted on a pin or bolt 26, said pin being supported in the outer wall of the casing B and 5 also in a flange 27 arranged as most clearly shown in Fig. 3. The dog F is also gravity actuated and of course cooperates with the same ratchet teeth 25.

- 10 To effect release of the brake, the annular release element G is employed, the same being mounted within the housing B as shown in Fig. 4. Said element G is of greater diameter than the ratchet wheel C and extends around the latter in normal position 15 but just slightly below the level of the operating teeth of the pawl and dog. Said element G, on diametrically opposed sides thereof, is provided with upwardly extending arms 28—28 that are merged at their upper ends so as to form a U-shaped cross arm as indicated at 29 in Fig. 4. The release lever H is pivotally attached to the cross arm 20 29 as by the bolt 30, said lever H being pivotally attached to the housing B by a bolt 31 at its end, as indicated in Fig. 5. Both the pawl E and the dog F are provided with laterally extended lugs 32—32 normally lying above the top edge of the element G as clearly shown in Fig. 4. To effect release, 25 the operator lifts the release lever H to the dotted position shown in Fig. 5, which of course causes the elevation of the element G. The latter in turn engages said lugs 32 of the pawl and dog and lifts them out of engagement with the ratchet teeth of the wheel C. In order to insure perfect safety of the operator, I preferably make the element G so that the upper edge thereof on the left hand side, as viewed in Fig. 4, will disengage the pawl E before the dog F is disengaged from the ratchet wheel so that there 30 is no danger of the operating lever being suddenly swung around to strike the brakeman.
- 40 45 Although I have herein shown and described what I now consider the preferred method of carrying out the invention, the same is merely illustrative and I contemplate all changes and modifications as come 50 within the scope of the claims appended hereto.

I claim:

1. In a brake for railway cars and the like, the combination with a vertically arranged 55 rotatable element adapted to effect winding of a brake chain or the like, of a housing, a single faced ratchet wheel within the housing and rotatable in unison with said element, of an operating lever extending to the 60 exterior of the housing and oscillatable in a horizontal plane, a pawl associated with said lever and cooperable with said ratchet wheel, a pivoted locking dog cooperable with said ratchet wheel, and means for disengaging the 65 pawl and dog from the ratchet wheel to

thereby release the latter and said element said means including a member common to and adapted to engage both said pawl and said dog.

2. In a brake for railway cars and the like, the combination with a vertically arranged rotatable element adapted to effect winding of a brake chain or the like, of a housing, a single faced ratchet wheel within the housing and rotatable in unison with said element, of an operating lever extending to the exterior of the housing and oscillatable in a horizontal plane, a pawl pivotally associated with said lever and cooperable with said ratchet wheel, a locking dog cooperable with said ratchet wheel, and means for first disengaging the said pawl and subsequently said dog from the ratchet wheel to thereby effect release of the latter, said means including a member common to and adapted to engage both said pawl and said dog.

3. In a hand brake adapted for application to flat cars and the like, the combination with a vertically extending brake-staff, of a housing adapted to be mounted on top of the flat car, a ratchet wheel rotatable in unison with said staff within the housing, an oscillatable operating lever, a gravity actuated pawl associated with said lever and cooperable with the ratchet wheel, a gravity actuated locking dog mounted within said housing and also cooperable with said ratchet wheel, and means for disengaging said pawl and locking dog from the ratchet wheel, said means including a member common to and adapted to engage both said pawl and said dog.

4. In a hand brake adapted for application to a flat car or the like, the combination with a vertically arranged rotatable element 105 adapted to effect winding of a brake chain, of a housing adapted to be secured to the top of said car, a ratchet wheel within the housing rotatable in unison with said element, an operating lever oscillatable in a horizontal 110 plane and pivotally mounted with respect to said ratchet wheel, a pawl associated with said lever and cooperable with the ratchet wheel, a dog cooperable with said ratchet wheel, a release lever, and means interposed 115 between said lever and the pawl and dog adapted to effect disengagement of the latter from the ratchet wheel.

5. In a hand brake adapted for application to a flat car or the like, the combination with a vertically arranged rotatable element 120 adapted to effect winding of a brake chain, of a housing adapted to be secured to the top of said car, a ratchet wheel within the housing rotatable in unison with said element, an operating lever oscillatable in a horizontal 125 plane and pivotally mounted with respect to said ratchet wheel, a pawl associated with said lever and cooperable with the ratchet wheel, a dog cooperable with said ratchet 130

wheel, a release lever, and means interposed between said lever and the pawl and dog adapted to effect disengagement of the latter from the ratchet wheel, said means comprising an annular member within the housing 5 pivotally connected to said release lever, projections on said pawl and dog normally

separated from said annular element but adapted to be engaged by the latter when the release lever is moved.

In witness that I claim the foregoing I have hereunto subscribed my name this 1st day of Sept. 1919.

FREDERICK B. TOWNSEND.
